UNITED STATES PATENT OFFICE.

WILLIAM JOSEPH SELLARS, OF WELLINGTON, NEW ZEALAND.

HEEL FOR FOOTWEAR.

1,366,601.

Specification of Letters Patent. Patented Jan. 25, 1921.

Application filed October 11, 1919. Serial No. 330,129.

To all whom it may concern:

Be it known that I, WILLIAM JOSEPH SELLARS, a citizen of the Dominion of New Zealand, and resident of 213 Tinakori road, 5 Wellington, in the Provincial District of Wellington, New Zealand, a subject of the King of Great Britain and Ireland, have invented certain new and useful Improvements in Heels of Footwear, of which the following is a specification.

This invention relates to foot wear having detachable heels or pads, which are provided for the purpose of enabling the heels to be easily and quickly repaired, and also 15 to insure greater comfort to the wearer than when ordinary solid fixed heels are used.

Hitherto detachable heels and pads have been secured on boots and shoes chiefly by the use of screws and bolts, which involve 20 the use of tools in their fixing on and removal from boots and shoes. Moreover apart from the fact that suitable tools are not always available, such detachable portions do not provide sufficient resiliency to 25 insure comfort, besides which the fastenings when said detachable portions become worn cause discomfort to the wearer.

The object of the present invention is to provide a detachable heel portion which can 30 be readily placed on and removed from either of a pair of boots or shoes by any ordinary person, without the aid of tools, and which at the same time and whether or not rubber is employed provides a degree of 35 resiliency in the heel, sufficient to give great comfort to the wearer when walking.

The invention consists in providing a plate of the same shape as the heel, with an inturned flange to form a groove around 40 its curved edge, said plate being either a fixture on the boot or shoe or removable with the detachable portion thereof, and engaging a plate or a lift either removable with the said detachable portion or a fixture on the 45 boot or shoe.

The detachable portion is attached to the fixed portion by sliding the former horizontally on to the latter, and causing the grooved plate to take the other plate or lift 50 either from the front or rear of the heel.

The plates are curved or hollowed so that when both are used their edges except at the front of the heel rest one on the other, or when only the grooved plate is employed the edge of the latter presses against the edge 55 of the lift, except at the heel front, whereby in both cases a space is left inside the heel, which enables the spring of the plates to provide resiliency when walking.

Holes in one plate and projections on the other plate, and lugs at the front of the grooved plate enable the detachable portions to be securely held to the fixed portions, while permitting the former to be easily 60 slipped off by hand, when required.

The invention will be more particularly described with reference to the accompanying drawing, in which:

Figure 1 is a side elevation of a heel according to this invention.

Figs. 2 and 3 show by means of cross sectional views alternative forms of the heel.

Fig. 4 is a plan view of a plate with an inturned edge.

Figs. 5 and 6 are a plan view and a sectional view through 6—6 Fig. 5 respectively of a plate suitable for carrying a detachable rubber portion.

Figs. 7 and 8 are a plan view and a sectional view through 8—8 Fig. 7 respectively of an alternative form of plate for carrying a detachable rubber portion.

Figs. 9 and 10 are a side elevation and cross sectional view respectively of a further form of heel.

Figs. 11 and 12 are similar views to Figs. 9 and 10 but illustrating a still further form of heel.

The invention is carried into effect by providing two heel portions, a portion 1, a fixture on a boot or shoe 2, and a detachable portion 3 to take the wear.

A metal plate 4 the same shape as the heel, is provided with an inturned flange to form a groove 5 around its edge, except at 95 the front 6 which is approximately straight.

The plate 4 can be either a fixture on the portion 1 (Figs. 2 and 10), or be removable with the detachable portion 3 (Figs. 3 and 12).

100

A plate 7 shaped to fit inside the grooved plate 4, can be either removable with the detachable portion 3 (Fig. 2) or a fixture on the portion 1 (Fig. 3).

- 5 When the grooved plate 4 is secured to the portion 1 as in Fig. 2, the plate 7 attached to the detachable portion 3 is slid into said plate 4, from the front of the heel, and when the plate 7 is attached to the portion 1 as in Fig. 3, the plate 4 attached to the detachable portion 3 is slid on to the plate 7 from the back of the heel, spaces being provided in each case between the plate 7 and the portion to which it is attached to enable the flanged edge of the plate 4 to engage the edge of the plate 7.

- In the case of a leather heel, where it is desired to use only a grooved plate 4, (Figs. 9 to 12) the latter can be attached to either the portion 1 or the detachable portion 3. In the former case the top lift 8 of the detachable portion 3 (Fig. 10) is slightly raised around its edges, and slid into the groove 5 from the front 6 of the heel. 20 When the plate 4 is attached to the detachable portion 3, the inturned edge of said plate is slid from the back of the heel between two lifts 9 of the fixed portion 1, said lifts 9 being prised slightly apart to permit this being done.

- When the detachable portion 3 is of rubber it is molded on to either the plate 4 or 7 as is required. One way of attaching the rubber to either the plate 4 or 7 is by means of a large headed rivet 11 projecting through the plate, and embedded in the rubber (Figs. 2 and 3), or as illustrated in Figs. 5 and 6 by riveting a smaller curved plate 12 to the plate 7, which plate 12 is 35 embedded in the rubber. A further way is to make cuts 13 in the plate 4 as shown in Fig. 7, and bend the cut portions 14 downward, the latter being embedded in the rubber.

- 40 The detachable portion 3 when of leather is attached to either plate as required, by nails 15. (Figs. 10 and 12.)

- The plate 4 or 7 when either is used on the fixed portion 1 is secured thereto by nails 50 15^a (Figs. 2, 3 and 10).

- To obtain resiliency in the heel, both the plates 4 and 7 are curved or hollowed and are attached to the portions 1 and 3 so that when fitted together their edges excepting 55 the front edges, meet, leaving a space 16 between the plates, the spring in the plates providing the resiliency.

- When the plate 4 alone is used the latter's curved edge, excepting at the front of the heel, presses against the edge of the top lift 8 of the portion 3 (Fig. 10), or against the edge of the bottom lift 9 of the portion 1, (Fig. 12), leaving the space 16 between the portions 1 and 3 as before.

- 60 To retain the portion 3 on the portion 1

either of the plates 4 or 7 can have projections 17 thereon, to spring into holes 18 in the opposite plate, when the two plates are fitted together, clearance spaces 19 being provided above or below the holes 18 as required in order that the projections 17 will not counteract the spring of the plates and prevent resiliency being obtained.

70 Where the plate 4 alone is used, as in Figs. 9 to 12, a projection 20 is provided at the front edge of said plate, and when the latter is slid on to a lift of the portion 1 from the back of the heel, the projection 20 is turned upward against the front of the portion 1.

75 When the upper lift of the detachable portion 3 is slid into the plate 4 attached to the portion 1, from the front of the heel the projection 2 is turned downward against the front of the portion 3.

80 The depth of the detachable portion 3 can be varied, and if desired it can be made equal to the full depth of the heel and be attached to the heel portion of the sole of the boot or shoe by any of the means before described.

85 I claim—

1. Improvements in a heel of footwear comprising a fixed portion, a detachable portion, a dished resilient plate the same shape as the heel secured to one of said portions and formed with an inturned curved edge to engage the edge of the other of said portions, said plate being curved in cross-section and its central part being spaced away from the portion to which it is not directly secured to provide an air space in which the central portion of the plate may move to aid in absorbing shocks transmitted to the heel.

90 2. Improvements in the heels of footwear, comprising a fixed portion, a detachable portion, a dished resilient plate of curved cross-section secured to one of said portions and formed with an inturned curved edge to engage the edge of a lift on the other of said portions, the central portion of said plate being spaced from the said lift to provide an air space in which the central portion of the plate may move when shocks are transmitted to the heel.

95 3. Improvements in the heels of footwear, comprising, a fixed portion; a detachable portion; a dished resilient plate of curved cross-section secured to one of said portions, and formed with an inturned curved edge; a dished resilient plate of oppositely curved cross-section secured to the other of said portions and having its curved edge engaged by the inturned edge of the other plate, the central portions of said plates being spaced apart, substantially as described and illustrated.

100 4. Improvements in the heels of footwear, comprising, a fixed portion; a detachable portion; a dished plate with an inturned

curved edge secured to one of said portions; a dished plate secured to the other of said portions and having its curved edge engaged by the inturned edge of the other plate; one of the plates being provided with holes and one of said portions being provided with clearance spaces, projections on one plate entering the holes in the other

5 plate and working in the clearance spaces, substantially as described and illustrated. 10

In testimony whereof I affix my signature in the presence of two witnesses.

WILLIAM JOSEPH SELLARS.
